WHEEL DRESSING DEVICE

Arthur Fumia, Rochester, N. Y., assignor to The Gleason Works, Rochester, N. Y., a corporation of New York

Application November 18, 1953, Serial No. 392,882

16 Claims. (Cl. 125—11)

The present invention relates to a device for dressing wheels, such as the abrasive wheels employed for grinding gears.

The device in its preferred form has two dressing elements mounted for swinging motion about a common axis across the opposite side faces of the wheel, which faces during a gear grinding operation form the opposite working sides of the gear teeth. The carriers of the dressing elements are moved axially in time with their angular motion in order that the side faces of the wheel will be dressed to the desired pressure angle, and to effect this axial motion each carrier has a cam follower engaging a plane-surfaced stationary cam. Spring means are arranged to act in an axial direction between the carriers to hold their followers against the cams. Each cam is adjustable independently of the other about an adjustment axis perpendicular to the axis of angular motion and lying in a plane which at least approximately bisects the arc of angular motion, this adjustment determining the pressure angle to which the side face of the wheel is dressed. Each cam is also adjustable independently of the other about an axis that is perpendicular to both the axis of angular motion and the pressure angle adjustment axis, and that is offset from the axis of angular motion by a distance equal to the radial distance of the follower from said axis of angular motion. By this adjustment the profile shape dressed on the wheel may be made straight, or it may be curved a desired amount either convexly or concavely.

For effecting the angular motion a fluid-pressure-operated actuating piston is provided for the carrier of each dressing element, each piston having a rack meshing with gear teeth on the carrier. The two pistons with their respective dressing elements are connected to move in opposite directions, the connecting means conveniently comprising a pinion rotatable on the support and meshing with a rack on each piston.

Other objects and advantages of the invention will appear from the following description made with reference to the accompanying drawings, wherein:

Fig. 1 is a front elevation of the dresser in operative relationship to an abrasive wheel to be dressed;

Fig. 2 is a side elevation of the wheel and dresser, with parts of the wheel broken away to show the dresser arms;

Fig. 3 is an enlarged fragmentary sectional view, taken along section line 3—3 of Fig. 1, showing the relationship of the dressing elements to the wheel;

Fig. 4 is a plan view of the dresser, with parts thereof broken away and appearing in horizontal section;

Fig. 5 is a view mostly in vertical section, in the plane indicated by section line 5—5 of Fig. 2, but with certain parts appearing in front elevation;

Fig. 6 is a vertical section approximately in the planes designated by the section line 6—6 of Fig. 5; and,

Fig. 7 is a diagram of a hydraulic circuit for operating the dresser.

- The dresser comprises a housing 10 adapted to be mounted, adjustably if desired, upon a gear grinding machine or other machine adjacent the abrasive wheel 11 thereof that is to be dressed. Journaled for rotation and axial motion in the housing are telescoping shafts 12 and 13 respectively supporting diamond tipped dressing elements 14 and 15. Shaft 12 is solid and secured thereon is an arm 16 in which the element 14 is mounted, while shaft 13 is tubular and carries a two-part arm 17, 18 mounting the element 15. As shown in Fig. 1 the parts 17 and 18 are relatively adjustable in the direction of the axis 21 of shafts 12 and 13 upon the loosening of a clamp nut 19. The effect of this adjustment is to vary the mean axial spacing of elements 14 and 15.
- 15 In the illustrated embodiment the wheel 11 is cup shaped and its axis of rotation, 22, is perpendicular to and vertically offset from the axis 21, the amount of the offset in this instance being equal to the radial distance of the points of the dressing elements from axis 21. The arrangement is such that as the shafts 12 and 13 rock about and move along axis 21 the elements 14 and 15 are respectively swung across the working outside and inside surfaces 23 and 24 of the wheel. The tip surface 25 may be dressed by other means, not shown.
- 20 Secured to shaft 12 within the housing is an arm 26 having secured to its outer end a cam follower, in the form of a hardened steel ball 27, engaged with plane surface 28 of a cam 29. The function of this cam is to effect axial motion of the unit comprising the dressing element 30 carrier, i. e. the arm 26, shaft 12 and the arm 16, and the dressing element 14 itself, in time with the angular motion of the unit about axis 21. The cam is adjustable about a horizontal axis 30 that is perpendicular to axis 21 and offset vertically from the latter by a distance equal to the radial distance of the center of ball 27 from axis 21. To enable this adjustment the cam has cylindrical journals 31 rotatable in a bracket 32 and on the cam is secured an adjusting arm 33 having an arcuate slot 34. Through this slot extends a clamp screw 35 which is threaded into a plate 36 that is secured by screws to the bracket 32 to hold the cam in assembly with the bracket. Upon the loosening of clamp screw 35 the cam 29 may be adjusted about its horizontal axis by manual movement of arm 33 to bring the plane face 28 to the desired angle relative to axis 21 in a vertical plane. The desired angle is obtained by spacing a pin 37 on plate 36 and a pin 38 on arm 33 at a distance that has been determined trigonometrically.
- 35 Similarly the shaft 13 is secured on an arm 26' having a cam follower 27' engaging plane face 28' of a cam 29', the latter having journals 31' received in a bracket 32' to enable it to be adjusted about a horizontal axis 30'. The adjustment is effected by first loosening a screw 35' which normally clamps arm 33' of the cam to plate 36', then turning the arm to the desired angle by spacing the pins 37' and 38' to a trigonometrically determined distance, and then retightening the screw 35'.
- 40 The arms 26 and 26' are urged apart along axis 21 by spring backed plungers 39 and 39', so that the followers 27 and 27' will follow the cam faces 28 and 28' throughout angular motion of the arms about the axis. As shown in Fig. 5 the plunger 39 is disposed in a bore in arm 26 and has a rounded nose bearing on a plane surface 41 on arm 26' while plunger 39' is disposed in a bore in arm 26' and bears on a plane surface 41' of arm 26. These plane surfaces 41 and 41' are perpendicular to axis 21 and of sufficient extent to contact the plungers throughout the angular travel of the arms.
- 45 As seen in Figs. 4 and 6, a plate 42 is secured by screws 43 to the bracket 32 to hold the latter in assembly with housing 10. The plate and the bracket have journal portions 44 rotatable in a bore in the housing to enable ad-
- 50
- 55
- 60
- 65
- 70

justment of the bracket about vertical axis 45. This axis is perpendicular to and intersects axis 21. The adjustment is effected by first loosening the clamp screws 46 which extend through arcuate slots 47 in the plate and then turning the plate and bracket to bring the axis 30 to the desired angle to axis 21. The angle may be set by spacing a steel ball 48 on the plate a trigonometrically-determined distance from a gaging surface 49 on the housing.

For rocking the shafts 12 and 13 a pair of pistons 51 and 52 are provided in cylinders in the lower part of the housing. Each piston has rack teeth 53 meshing with gear teeth 54 on the cam follower arms 26 and 26'. Each piston also has another set of rack teeth 55 meshing with a pinion 56 that is rotatable on a stud 57 secured to the housing. With this arrangement the shafts 12 and 13 are positively geared together for rocking motion in opposite directions.

The dresser may be controlled in various ways, either manually or automatically in conjunction with the operating cycle of the grinding machine of which it is a part. A manually controlled hydraulic system shown in Fig. 7 includes a sump 58 containing hydraulic fluid, a pump 59, a reversing valve 61, supply line 62 and return line 63 extending to the valve respectively from the pump and the sump, and lines 64 and 65 extending between the valve and the respective ends of the cylinders containing pistons 51 and 52. In line 65 is a throttle valve 66 and a by-pass which contains a check valve 67.

With the valve in the position shown, hydraulic pressure is applied by pump 59 through line 62, valve 61 and line 64 against the left end of piston 51 and the right end of piston 52, holding the dressing elements 14 and 15 in the idle positions thereof shown in broken lines at 14' and 15' in Fig. 3. To dress the wheel the dresser is first conditioned for the dressing stroke by shifting the valve 61 to connect lines 62 and 65, and also to connect lines 64 and 63. Fluid from the pump passes through lines 62 and 65 into the cylinder chambers to move piston 51 to the left and piston 52 to the right, thereby swinging the dressing elements to their positions shown in full lines in Fig. 3. Fluid displaced by the pistons is returned to the sump through lines 64 and 63. In this action the check valve 67 opens so that the piston motion is not impeded by throttle valve 66. Next the wheel 11 is advanced axially a slight amount, by any suitable means (not shown), to provide stock for dressing. Then the valve 61 is shifted again to the position shown. Fluid under pressure flowing through lines 62 and 64 shifts piston 51 to the right and piston 52 to the left, thereby moving the elements 14 and 15 from their full line positions to their dotted line positions 14' and 15' and dressing surfaces 23 and 24 on the wheel. The rate of this action is determined by the adjustment of throttle valve 66 which governs the rate of return fluid flow through lines 65 and 63 to the sump, the check valve 67 being closed at this time.

In Fig. 3 is shown a line 22' which extends in the direction of the wheel axis 22. The pressure angles of surfaces 23 and 24, that is the angles which these surfaces make with line 22', are designated A and B respectively. As the arm 26 and shaft 12 swing, in a direction counterclockwise in Fig. 3, to carry the element 14 between its full and dotted line positions shown in Fig. 3, the center of spherical cam follower 27 moves in an arcuate path 68, which as shown in Fig. 6 is tangent to axis 30. If surface 28 is adjusted about axis 45 (and also about 30) into perpendicularity with axis 21, then the center of follower 27 will remain in a plane perpendicular to axis 21 throughout its motion along path 68. No axial motion will be imparted to shaft 12 and element 14, and the pressure angle A to which the surface 23 is dressed will be zero. However if the cam surface 28 is inclined about axis 45 so that it is at an acute

angle to axis 21, then as the follower 27 moves along path 68 it will also have a motion along axis 21, and the shaft 12 and element 14 will move as a unit with it. The greater such axial motion the larger will be the pressure angle A to which the surface 23 is dressed. It will thus be seen that the pressure angles A and B of the opposite sides 23 and 24 of the wheel can be made of any desired practical value by the aforementioned adjustment of brackets 32 and 32' about their respective axes 45 and 45'.

Referring further to Fig. 6, it will be seen that if the cam 29 is so adjusted about axis 30 that axis 45 is parallel to the plane of surface 28, then the vertical component of motion of follower 27, as it moves along arcuate path 68, is of no consequence as concerns axial motion of the element 14. The element will dress the surface 23, Fig. 3, to substantially straight profile shape. However if surface 28 is inclined relative to axis 45 then as the follower moves along arc 68 from end point 69 to mid-point 71 the element 14 will be given a component of axial motion. As the follower moves from mid-point 71 to end point 72 an opposite component of axial motion will be imparted to the diamond. These components of motion are added to or subtracted from the axial motion which results from the inclination of surface 28 about vertical axis 45. Therefore depending upon the direction of the adjustment of the cam about axis 30, the profile 23 may be made of convex form, as indicated at 23', or of concave form as indicated at 23''. Similarly by varying the direction of inclination of cam 29' about axis 30', either a convex profile 24' or a concave profile 24'' may be dressed on the wheel. The amount of concavity or convexity will of course depend upon the degree of inclination of the cams about axes 30 and 30'. Access to the interior 35 of the housing, for the purpose of making the adjustments of cams 29 and 29' about axes 30 and 30', can be had by removing the cover plate 73.

It will be noted that regardless of the angle of adjustment of cam 29 about axis 30, the arc 68 described by the center of ball 27 will be tangent to axis 30 at mid-point 71. The direction of arc 68 at point 71 thus depends solely upon the angle to which the cam is adjusted about axis 45. Hence the pressure angles to which the surfaces 23 and 24 are dressed are not affected by adjustment of cams 29 and 29' about their axes 30 and 30'. However the profile curvatures to which the surface 23 and 24 are dressed are affected to a slight extent by changes in pressure angle effected by adjustment of the cams about their vertical axes 45 and 45'. The approximate amount of the changes is shown by the following:

Let

$$a_c = \text{radius of cam follower arm 26 to center of ball 27}$$

$$a_d = \text{radius of arm 16 to point of dressing element 14}$$

$$\phi = \text{pressure angle}$$

$$u = \text{angular setting cam about axis 45}$$

$$R_p = \text{radius of profile curvature of surface 23}$$

$$v = \text{angular setting of cam about axis 30}$$

$$\tan u = \frac{a_d}{a_c} \tan \phi$$

$$\tan v = \frac{a_d^2 \cos u}{R_p \cos^3 \phi a_c}$$

At least as applied to gear grinding machines the dresser housing 10 is preferably mounted for adjustment both radially and longitudinally of wheel axis 22. The radial adjustment enables wheels of different diameters to be dressed, while the axial adjustment enables the curved profiles, such as 23', 24', 23'' and 24'', to be placed in

any desired position along the wheel axis and relative to the tip surface 25 of the wheel.

It will be understood that the dresser described and illustrated herein represents only the preferred embodiment of the inventive principles involved, and that these principles may be incorporated in various physical forms and arrangements of parts without departing from the spirit of my invention or from the scope of the appended claims.

What I claim is:

1. A wheel dressing device comprising a support, a dressing element carrier mounted on the support for angular motion and also for motion in the direction of the axis of such angular motion, a cam on the support and a follower for the cam on the carrier for effecting the motion in the direction of the axis in time with the angular motion, and means whereby the cam may be adjusted universally on the support about an intermediate point along the arc of angular motion of the follower.

2. A wheel dressing device according to claim 1 in which the surface of the cam engaged by the follower is a plane surface.

3. A wheel dressing device according to claim 1 in which the means whereby the cam may be adjusted universally comprises means whereby the cam may be adjusted on the support about a first adjustment axis that is perpendicular to and intersects the axis of angular motion of the carrier, and means whereby the cam may also be adjusted on the support about a second adjustment axis that is perpendicular to and offset from said axis of angular motion and is perpendicular to and intersects the first adjustment axis.

4. A wheel dressing device according to claim 1 in which there are means for swinging the carrier about its axis of angular motion and yieldable means for urging motion of the carrier in the direction of said axis to maintain the follower against the cam.

5. A wheel dressing device according to claim 1 in which the follower has a spherical surface engaging the cam and said arc of angular motion is the arc traversed by the sphere center of said surface.

6. A wheel dressing device comprising a support, a dressing element carrier mounted on the support for angular motion and also for motion in the direction of the axis of such angular motion, a cam on the support having a plane surface and a follower on the support engageable with said surface for effecting the motion in the direction of the axis in time with the angular motion, means whereby the cam may be adjusted on the support about a first adjustment axis that is perpendicular to the axis of angular motion and the cam also about a second adjustment axis that is perpendicular to both of the aforementioned axes and is tangent to the arc of angular motion of the cam follower.

7. A wheel dressing device comprising a support, a pair of dressing element carriers mounted on the support for independent motion angularly about a common axis and also along the axis, a cam for each carrier on the support and a follower for each cam on the related carrier, each cam having a plane surface engaged by its follower, and means whereby each cam may be adjusted universally on the support about an intermediate point along the arc of angular motion of its follower.

8. A wheel dressing device according to claim 7 further comprising means to swing the carriers about said common axis and yieldable means acting between said carriers for urging them along said axis to maintain the followers against the cams.

9. A wheel dressing device according to claim 8 in which the means to swing the carriers comprises a means to move them alternately in opposite directions.

10. A wheel dressing device according to claim 7 in which there is a fluid pressure operated actuating piston for each carrier movable in a cylinder in the support, each piston having a rack meshing with gear teeth on

the related carrier, and there is a means connecting the pistons for opposed motion.

11. A wheel dressing device according to claim 10 in which the means connecting the pistons for opposed motion comprises a pinion rotatable on the support and meshing with a rack on each piston.

12. A wheel dressing device comprising a support, a pair of dressing element carriers mounted on the support for independent motion angularly about a common axis and also along the axis, a fluid pressure operated actuating piston for each carrier movable in a cylinder in the support, each piston having a rack meshing with gear teeth on the related carrier, a pinion rotatable on the support and meshing with a rack on each piston for connecting the pistons for opposed motion, a cam for controlling the axial motion of each carrier, each cam having a plane surface engaged by a cam follower on the related carrier, means whereby each cam may be adjusted about a first adjustment axis which is perpendicular to and intersects said common axis, means whereby each cam may be adjusted about a second adjustment axis which is perpendicular to said common axis and offset therefrom by a distance equal to the radial distance of the cam follower from said common axis, the second adjustment axis being perpendicular to and intersecting the first adjustment axis, and spring means acting between said elements for urging relative axial motion of them to maintain the followers against the cams.

13. A wheel dressing device comprising a support, a dressing element carrier mounted on the support for motion angularly about a common axis and also along the axis, a cam for the carrier on the support having a plane surface engaged by a cam follower on the carrier, yieldable means for urging axial motion of the carrier to maintain its follower against the related cam, and means to adjust the cam about an adjustment axis that is perpendicular to said common axis and that lies in a plane containing said common axis which approximately bisects the arc of angular motion of the carrier whereby the motion of the carrier will have a component along said common axis that is unidirectional during the angular motion in each direction.

14. A wheel dressing device comprising a support, a dressing element carrier mounted on the support for motion angularly about a common axis and also along the axis, a cam for the carrier on the support having a plane surface engaged by a cam follower on the carrier, yieldable means for urging axial motion of the carrier to maintain its follower against the related cam, and means to adjust the cam about an axis which is perpendicular to said common axis and offset therefrom by a distance equal to the radial distance of the cam follower from said common axis whereby during the angular motion of the carrier in each direction it may have a component of motion along the common axis which reverses at a mid-point the angular motion.

15. A wheel dressing device comprising a support, a pair of carriers mounted on the support for angular and axial motion about and along a common axis, a wheel-dressing element mounted on each carrier, means connecting said carriers for angular motion in unison with each other, and means for moving them axially independently of each other in time with their angular motion.

16. A wheel dressing device comprising a support, a pair of telescoping shafts mounted on the support for angular and axial motion, a carrier arm on each shaft and a wheel dressing element on each arm, means for effecting angular motion of the two shafts in unison with each other, and means for moving the shafts axially independently of each other and in time with their angular motion.
